[57] CLAIM

The ornamental design for a carrier attachment for invalid walkers, as shown and described.

DESCRIPTION

FIG. 1 is a perspective view of a carrier attachment for invalid walkers showing my new design;

FIG. 2 is a top plan view thereof;

FIG. 3 is a bottom plan view thereof;

FIG. 4 is a front elevation view thereof;

FIG. 5 is a side elevation view thereof; and

FIG. 6 is a side elevation view thereof opposite the side illustrated in FIG. 5.
